UNITED STATES PATENT OFFICE.

RICHARD M. VAN VALKENBURGH, OF KANSAS CITY, MISSOURI, ASSIGNOR TO IRVING-PITT MANUFACTURING COMPANY, OF KANSAS CITY, MISSOURI, A CORPORATION.

LOOSE-LEAF BINDER.

Application filed May 7, 1926. Serial No. 107,412.

This invention relates to loose leaf binders, and particularly to the back member thereof to which the binder sides are hingedly connected, and which includes the well-known leaf-supporting members adapted to carry telescoping posts and which travel toward and from each other as sheets are removed or inserted and as the binder is required to hold a greater number of 10 sheets.

One of the objects of the instant invention is to provide an improved back member for loose leaf binders which includes resilient means for constantly exerting a yielding force against the two leaf-supporting members to snap them to the open position when the novel locking device is released.

It is well known in the art that post binders of the character set forth do not have what is termed one hundred per cent expansion, that is, the distance between the leaf-supporting members when open is not twice the distance between the same when closed.

Another object of the instant invention is, therefore, to provide a binder which has one hundred per cent expansion and which is adapted to be used with the well known binder channel without altering the same.

Yet a further object of this invention is the contemplation of a loose leaf binder back which has simple and durable mechanism for locking and unlocking the movable leaf supporting members in any predetermined position, which mechanism is quickly operated, is strong and positive in its action, and includes but comparatively few parts.

A still further object of this invention is the provision of a lock-operating device which is movable from the locked to the unlocked position through a very slight movement of the actuating key.

The many novel features of the present invention are hereinafter fully set forth in the specification referring to the accompanying drawings in which:

Figure 1 is a plan view of a loose leaf binder back, made in accordance with the invention and showing the leaf-supporting members in the extended position.

Fig. 2 is a similar view with the leaf-supporting members in the closed position.

Fig. 3 is a longitudinal central section taken on line III-III of Fig. 2.

Fig. 4 is a cross section through the binder back taken on line IV-IV of Fig. 1. 55

Fig. 5 is a similar section taken on line V-V of Fig. 2.

Fig. 6 is an enlarged detail fragmentary perspective view showing the lock and operating member. 60

Fig. 7 is a perspective view of one of the dogs entirely removed from the mechanism, and,

Fig. 8 is a fragmentary plan view showing another manner in which the ends of the leaf-supporting members may be slidably interconnected. 65

Similar reference characters refer to like parts throughout the several views, and the numeral 9 designates a back member which is arcuate in cross section, and carries the usual end caps or supporting pieces 10. 70

A pair of leaf-supporting members 12 and 13 respectively are preferably formed of right-angled plates, one of the sides of each of which carry posts 14 adapted to telescope with tubes 15 mounted on opposite like members. 75

Members 12 and 13 are mounted on back 9 for movement toward and from each other by a bracket 16, rigidly secured to the inner side of back 9 and below and intermediate the members 12 and 13, as shown in Fig. 1. 80

The means for slidably mounting these leaf-supporting members also includes the locking device, and is here illustrated in one embodiment to be the above-mentioned bracket 16, each of the two sides of which has a slot 17 formed therethrough to receive arms 18 and 19, extending laterally from members 12 and 13 respectively. 85

These arms slidably engage and overlap each other, arm 19 riding over the top of arm 18, and may be locked against movement by a pair of locking dogs 20 and 21, each of which has a slot 22 and 23 respectively which registers with slots 17 in bracket 16 when in place, and through which arms 18 and 19 pass. An opening 24 cut in the top wall of bracket 16 receives jaws 25 and 26 of dogs 20 and 21 respectively, allows both to rest on the projected portion or arm of one leaf holding member and permits them to rock when the depending walls are forced apart by the lock-actuating shaft 27. 90

To carry out one of the main features of the invention, which is to procure one hun- 100
105

dred per cent expansion, each of members 12 and 13 has a slot S and S' respectively, through which the ends of arms 19 and 18 respectively pass when the binder is closed as shown in Fig. 5. These ends of arms 18 and 19 are projected into and housed within the well-known binder channel, (not here shown), which is affixed to the sides of members 12 and 13 when the device 10 is assembled.

The use of the herein-described novelly constructed lock permits arms 18 and 19 to overlap to the extent just set forth, and makes it possible to quickly secure the binder 15 in any adjusted position.

The lock-actuating shaft, which may be made in other forms if desired, is adapted to be moved longitudinally of the back and is supported for rotary and longitudinal 20 movement, at its innermost end by pintle 28, journalled in a wall of bracket 16 as shown in Fig. 3. The other end thereof is disposed adjacent opening 29 in end cap 10, and is squared as at 30, or otherwise formed 25 to be engaged by a key or the like. A portion of the length of shaft 27 is screw-threaded as at 31 and passes through tapped openings in bracket 32 which causes a longitudinal movement when the shaft is turned.

30 A conical or wedge portion 33 is formed on that part of the shaft 27 passing between the walls of dogs 20 and 21, and forces the jaws 25 and 26 respectively thereof downwardly when rotated to cause threads 31 to 35 force it in the direction of arrow in Fig. 3. This action fulcrums the jaws of the dogs to a position from the released position, shown in Fig. 4, to the gripping or locked position, shown in Fig. 5. It is to be noticed that the slots 22 and 23 in dogs 20 40 and 21 respectively are wide enough to permit this action, and when the arms 18 and 19 are so pressed together, they will not pull apart or be allowed to take on relative sliding movement.

45 It has been found desirable to exert this gripping pressure evenly along the jaws 25 and 26 by forming a rib 34 centrally of the depending wall of each dog. Thus, the action is even and the force imparted from the wedge portion 33 is equally distributed.

50 It is an advantage, in making the dog-operating wedge portion 33, to construct the same with an angle or pitch great enough to permit actuating the dogs 20 and 21 from the locked to the unlocked position, or vice versa, when the shaft 27 is given one complete turn. This action is also based upon the relation of the screw threads to the angle 55 of portion 33, and these parts should all be correlated to permit locking or unlocking of the dogs with the slightest possible movement of shaft 27.

55 When the herein-described locking parts are released, it is desirable to have means

for opening the leaf-supporting members 12 and 13. This means for opening the members may be in the form of a pair of springs 35, affixed as at 36 to each member 12 and 13, and always exerting a yielding outward 70 pressure to urge the members apart.

Guide or movement-controlling mechanism is also provided adjacent each end of the binder back 9, which comprises the brackets 32 and 32', to each of which is pivotally affixed as at 37, an arm 38 which extends equidistantly on each side of the pivot pin 37 to pivotally engage one end of links 39 and 40, the other ends of which are pivotally secured to leaf-supporting members 80 12 and 13 respectively. Pivotal point 37 is centrally located between members 12 and 13, and through this arm and link construction, the travel of each member 12 and 13 away from the center of back 9 is maintained at the same speed. A stop pin 41 should be positioned in the path of travel of each arm 38 to limit the movement of all parts.

It is obvious, that no lost motion or play 90 can possibly be present in a binder constructed in accordance with this invention. If desired, in lieu of the arm and link device, pairs of arms 50 and 51, having slots 52 and 53 respectively, may be secured to 95 leaf-supporting members 12 and 13 respectively as shown in the modified form, Fig. 8 with both slots engaging a pin on brackets 32, 32'.

100 While one desirable form of the binder and its various parts has been shown, it is desired to be limited in the construction of the same only by the appended claims.

105 What I claim and desire to secure by Letters Patent is:

1. In a loose leaf binder, two leaf-supporting members movable relative to each other each having a portion thereof slidably overlapping a like portion of the other, means, including a pair of dogs, for maintaining said overlapped portions in sliding engagement and means movable to position between said dogs for causing the same to hold the members against relative movement.

110 2. In a loose leaf binder, two leaf-supporting members movable relative to each other, means, including a pair of slotted fulcrumed dogs, for securing said members against movement and means adapted to actuate each of said dogs to the locked position, each of said leaf-supporting members having a portion passing through the slots 115 through said dogs.

120 3. In a loose leaf binder, two leaf-supporting members movable relative to each other, means, including a pair of slotted dogs, for slidably supporting said members and locking the same against relative movement, and means for simultaneously swing- 125 130

ing each of said dogs to the locking position, a portion of each member passing through each slot in each of said dogs.

4. In a loose leaf binder, a back member, 5 a pair of leaf-supporting members carried thereby for movement toward and from each other transversely of said back member, a lock comprising a pair of fulcrumed dogs for securing said supporting members 10 against movement and a dog-actuating shaft carried by the back and adapted to move longitudinally thereof as it is rotated to move said dogs.

5. In a loose leaf binder, a back member, 15 a pair of leaf-supporting members carried thereby for movement toward and from each other transversely of said back member, a lock including a pair of fulcrumed dogs adapted to secure said supporting members 20 against movement and means for actuating said dogs, both dogs of said lock being slidably engaged by a portion of each of the two leaf-supporting members.

6. In a loose leaf binder, a back member, 25 a pair of leaf-supporting members carried thereby for movement toward and from each other, an arm extending from each leaf-supporting member to slidably overlap each other, a lock including a pair of 30 co-acting dogs for securing said arms against movement and means entering between said dogs for actuating said lock from the end of said back member.

7. In a loose leaf binder, two leaf-supporting members, a laterally extending arm integral with each member, a pair of locking dogs adapted to grip said arms and means for moving said dogs to the locked position.

40 8. In a loose leaf binder, a back member, a pair of leaf-supporting members carried thereby for movement toward and from each other, each leaf-supporting member having an arm extending therefrom adapted 45 to slidably overlap the arm of the other, a lock for securing said arms against relative movement including a pair of dogs each having a slot formed in its depending body wall through which said overlapped arms 50 pass and a jaw, for engaging one of said

arms, and means for actuating said lock including a wedge member adapted to enter between the walls of said dogs.

9. In a loose leaf binder, a back member, 5 a pair of leaf-supporting members carried thereby for movement toward and from each other, an arm extending from each leaf-supporting member adapted to slidably overlap each other, a lock for securing said 10 arms against relative movement comprising a bracket secured to said back having slots in the opposite sides thereof, a pair of dogs each having a slot formed in the depending 15 wall thereof and a jaw projecting at an angle along its upper edge, said jaws of the dogs being disposed toward each other to rest on one of the two overlapping arms which pass through all of said slots and a lock-actuating means including a wedge 20 adapted to enter between the depending 25 walls of said dogs, whereby the jaws thereof are caused to lock overlapped arms against movement.

10. In a loose leaf binder, movable leaf-holding members, resilient means for forcing said members apart and manually operable means for locking said members against relative movement including a pair of fulcrumed dogs each having a jaw engaging a portion of one leaf-holding member and 30 means for moving each of said dogs into the locking position.

11. In a loose leaf binder, a back member, a pair of leaf-supporting members carried thereby for movement toward and from each other transversely of said back member, each leaf-supporting member having an arm extending therefrom adapted to overlap the arm of the other, a lock including a pair 35 of jaws for gripping said arms to hold the same against relative movement and means for moving said jaws to the locking position, including a shaft having a jaw-operating member thereon, said shaft being adapted when rotated to move said member to and from the jaw-engaging position.

In testimony whereof I hereunto affix my signature.

RICHARD M. VAN VALKENBURGH.
